[57] CLAIM

The ornamental design for a handle for shopping bags,
as shown and described.

DESCRIPTION

FIG. 1 is a perspective view of a handle for shopping bags showing my new design;

FIG. 2 is a side elevational view thereof, both sides
being identical;

FIG. 3 is an end elevational view thereof, both ends
being identical;

FIG. 4 is a top plan view thereof;

FIG. 5 is a bottom plan view thereof;

FIG. 6 is a top plan view of a second embodiment of the
design of FIG. 1 in its open position;

FIG. 7 is a bottom plan view of FIG. 6;

FIG. 8 is an end elevational view of FIG. 6, both ends
being identical;

FIG. 9 is an end elevational view of FIG. 6, in its position
of use.
